FRANK P. VINCENT, OF ELYRIA, OHIO, ASSIGNOR, BY MESNE ASSIGNMENTS, TO STEEL AND TUBES, INC., OF CLEVELAND, OHIO, A CORPORATION OF OHIO

METHOD OF BRAZING

Application filed October 4, 1926. Serial No. 139,331.

This invention relates to a method of brazing. More particularly it relates to a method of heating a plurality of elongated articles, such as tubes, for the purpose of brazing or the like.

An object of the invention is to provide a process in which articles may be uniformly heated on all sides.

Another object is to provide a process in which all articles will be heated alike, irrespective of the part of the heated chamber through which they pass.

Another object is to provide a process in which the temperatures of different parts of a heated chamber may be readily and independently controlled.

Another object is to provide a process by which articles may be mechanically conveyed and at the same time uniformly heated.

Other objects will hereinafter appear.

The invention will be better understood from the description of one practical embodiment thereof illustrated in the accompanying drawings, in which—

Fig. 1 is a plan view of the furnace and associated parts, the upper part of the furnace being shown in section taken on line 1—1 of Fig. 2;

Fig. 2 is a side elevation of the apparatus shown in Fig. 1, parts being shown in section taken on line 2—2 of that figure; and

Figs. 3 and 4 are cross sections of the furnace and the chamber, taken on lines 3—3 and 4—4, respectively, of Fig. 2.

Figure 5 is a slightly enlarged view of a conveyor bar with tubes thereon shown in section.

The furnace consists of a bottom 1, a top 2, an intermediate horizontal wall 3, sides 4 and 5, and ends 6 and 7. The intermediate wall divides the interior of the furnace into two chambers or compartments, a lower or heating chamber extending throughout the furnace and having openings 9 and 10 in its ends, and an upper or combustion chamber 11 extending partially over the heating chamber. The side walls 4 and 5 converge above the horizontal wall 3 to an opening 12 through which fuel is introduced and are provided with oblique passages 13 and 14 admitting air

to the combustion chamber. The air admitted is controlled by doors or dampers 15 at the outer ends of the passages. A passage 16 allows the burning gases to pass from the end of the combustion chamber remote from opening 12 to the heating chambers. In order to direct the gases through this passage and prevent the setting up of eddy currents, the inner surface of the end wall 6 is downwardly and outwardly inclined in the combustion chamber and below this extends vertically down to opening 9.

At the end of the heating chamber opposite passage 16 is a stack 17. Just before the stack at 18 the ceiling of the heating chamber has a short, depending step, and the end wall 7 depends slightly further than this step, as shown.

It will be noted that most of the combustion chamber 11, the passage 16, the heating chamber 8 and the stack 17 are all of the same width and that the sides of all extend vertically.

The furnace is constructed of refractory material, such as fire brick, and may be protected and supported by a metal sheathing as shown. The entire structure is supported on legs 19.

Extending along the bottom of the heating chamber and projecting through the openings at both ends are two parallel pipes 20. These are supported a little above bottom 1 by spaced refractory blocks 21 and are connected, at their downturned projecting ends, with a suitable water supply or the like by 75 the circulation of which they may be kept cool enough to not be damaged by the furnace heat.

Outside the furnace, and in alignment with pipes 20, are two other pairs of parallel pipes 22 and 23 supported, respectively, on tables 24 and 25. These three pairs form a track for a chain conveyor by which articles are carried through the furnace.

The conveyor consists of two chains driven by sprockets 26 and running over idler sprockets 27. The sprockets 26 are rotated in a counter-clockwise direction as shown in Fig. 2, by any suitable source of power, through gear 65 ing 28 and controlled by a clutch 29.

Beyond the chain conveyor, on table 25, is a series of rollers 30 to which the chain conveyor may deliver articles and this part of the table is also provided with a transfer cradle composed of shaft 31 and bars 32 by the rotation of which articles can be removed laterally from the rollers.

The chains of the conveyor carry at frequent intervals cross bars 33 arranged to slide along the tops of the track formed by the pipes above described. These cross bars carry the articles which are to be heated and may have their upper edge notched as shown or otherwise suitably shaped to retain the articles. It will be noted that when in the heating chamber the ends of the bars are well clear of the side walls, there being in practice about three inches between the ends of bars and the walls, and there is a considerable space between the bars and the bottom of the furnace.

This permits the hot gases to readily reach every side of each article and thus heat it uniformly throughout.

Due to the flaring sides of the combustion chamber near the fuel inlet opening, the fuel air and burning gases flow along this chamber without setting up serious eddy currents. The gases also pass through the passage 16 and along the heating chamber without material disturbance. It is, therefore, possible, by controlling the air admitted through ports 14 and 15, to control the temperature at different parts of the heating chamber, thus always heating the articles to the desired temperature. This is particularly important in brazing, where the metal must be heated sufficiently to fuse and must not be permitted to burn.

The chain conveyor carries the articles into the furnace at the stack end, where the gases are comparatively cool, and then, as the articles become heated, through progressively hotter parts of the furnace, thus extracting the greatest practicable amount of heat from the gases.

The conveyor may be operated continuously at such a speed that the articles are heated any desired amount as they pass through the furnace, or may be caused to stop when the articles have been carried into the furnace and then operated to remove them after they have been heated for any desired period.

Due to the arrangement of the conveyor parts, the heated gases have ready access to all sides of the articles, so that no side is heated substantially more than any other.

While I have described the illustrated embodiment of my invention in some particularity, obviously it may be applied in many other ways and I do not, therefore, limit myself to the precise construction shown but claim as my invention all variations, modifications and embodiments coming within the scope of the appended claims.

I claim:

1. The process of brazing tubes which comprises moving a plurality of tubes simultaneously through a chamber, controlling the temperature of the chamber, so that the temperature of the tubes is substantially uniform on any transverse plane, and controlling the speed at which the tubes are moved so that brazing material is heated sufficiently to fuse but not to burn.

2. The process of brazing tubes which comprises applying brazing material to the seams of the tubes, arranging the tubes in groups, each of which comprises a plurality of tubes in spaced side-by-side relation, passing the groups successively through a furnace from the cooler end to the hotter end thereof, while maintaining the tubes at a distance from all walls of the furnace, controlling the temperature in the furnace by admitting air at a plurality of points so that the temperature of the tubes is substantially uniform on any transverse plane, and controlling the speed at which the tubes are moved so that the brazing material is heated just sufficiently to insure proper fusion.

3. The process of brazing tubes which comprises applying brazing material to the seams of the tubes, arranging the tubes in groups, each of which comprises a plurality of tubes in spaced side-by-side relation, passing the groups successively through a chamber while maintaining the tubes at a distance from all walls of the chamber, controlling the temperature in the chamber, and controlling the speed at which the tubes are moved so that the brazing material is heated just sufficiently to insure proper fusion.

4. The method of brazing which comprises introducing heated gas into a chamber, passing articles to be brazed through the chamber at such a speed that they are heated by the gas to a brazing temperature, and maintaining substantially uniform the temperature in the chamber in any vertical plane at right angles to the path of travel of the articles.

5. The method of brazing which comprises introducing heated gas into a chamber, passing articles to be brazed through the chamber in such a manner that they are heated by the gas to a brazing temperature, and introducing cooling gas into localized portions of the heated gas whereby the temperature of the latter is maintained substantially uniform in any vertical plane at right angles to the path of travel of the article.

6. The method of brazing which comprises passing heated gas into a chamber, passing articles to be brazed through the chamber and heating them to a brazing temperature while maintaining them in spaced relation to the walls of the chamber, and maintaining the temperature in the chamber substantially

uniform in any vertical plane at right angles to the path of travel of the articles.

6 7. The method of brazing which comprises passing heated gas through a chamber, controlling the temperature of the gas so that in any given plane at right angles to its direction of travel the temperature of the gas is substantially uniform, and passing articles to be brazed through the chamber in a 10 direction opposite to the travel of the gas and out of contact with the chamber walls and controlling the travel of the articles so that they are gradually heated to brazing temperature.

15 8. The method of brazing tubes which comprises passing heated gas through a chamber, passing tubes to be brazed through the chamber in a direction opposite to that of the gas and causing the tubes each to be heated substantially uniformly in any given transverse plane and gradually heated up to the brazing 20 temperature.

25 9. The method of brazing tubes which comprises passing heated gas through a chamber, passing tubes to be brazed through the chamber in a direction opposite to that of the gas and causing the tubes each to be heated substantially uniformly and all to be heated to substantially the same temperature 30 in any given transverse plane and gradually heated up to the brazing temperature.

In testimony whereof I hereunto affix my signature.

FRANK P. VINCENT.
